UNITED STATES PATENT OFFICE.

EDWARD R. LINEBAUGH, OF BARBERTON, OHIO, ASSIGNOR TO THE DIAMOND MATCH COMPANY, OF CHICAGO, ILLINOIS, A CORPORATION OF ILLINOIS.

SHEET-FEEDING MECHANISM.

Application filed January 17, 1924. Serial No. 686,720.

This invention relates to sheet feeding mechanism designed for use especially, though not exclusively, in connection with machines for bronzing sheets of cardboard or the like. In the operation of such machines the sheets are taken from a printing press in comparatively small quantities and are delivered severally to the machine, so that the bronze will be dusted on the sheets before the ink becomes dry. Heretofore the sheets have been placed in two piles side by side on a feed bed or table at the front of the bronzing machine, and then manually fed into the machine by two attendants, one located at each side of the machine.

The object of my invention is to provide means whereby relatively large and heavy printed sheets, such as thick paper or cardboard, are automatically and rapidly removed from a pile or piles and accurately fed to a bronzing or other machine; and to this end the invention comprises novel features of construction and combinations of parts which will be hereinafter described and claimed.

In the drawings—

Figure 1 is a side elevation of sheet feeding mechanism embodying my invention, as applied to a bronzing machine, only so much of the latter being shown as is necessary to illustrate the invention.

Fig. 2 is a plan of the sheet feeding mechanism.

Fig. 3 is a longitudinal vertical section, enlarged, as on the line 3—3 of Fig. 2, showing the cam structure for one of the reciprocating feed bars; the forwarding tapes, and adjuncts.

Fig. 4 is a vertical section through the said cam structure, as on the line 4—4 of Fig. 3.

Fig. 5 is a similar section, as on the line 5—5 of Fig. 2, showing the registering fingers, the adjacent sheet depressing and sheet positioning fingers, and adjuncts.

Fig. 6 is a perspective view illustrating one of the sheet positioning fingers and its supporting parts.

Referring to the drawings, 10 designates the sheet carrying cylinder of a bronzing machine of the type illustrated in Letters Patent of the United States No. 1,107,773, dated August 18, 1914. The usual inclined

feed bed 11 of the machine is provided at 55 that end adjacent the peripheral path of the cylinder with oscillatory registering fingers 12 which are operable to position the leading edge of the sheet in the path of the usual grippers 13 that are carried by 60 the cylinder. The fingers are supported by a transverse shaft 14 journaled in brackets 14' on the main frame and having at one end a crank-arm 15 which is jointed to a bar 16 under the control of a cam 17 on the 65 power-driven cylinder shaft 18. This cam is of proper contour to effect through the bar and crank connections the desired intermittent operation of the registering fingers to position and release the sheet in timed 70 relation to the rotation of the carrying cylinder.

19 designates a series of vibratory pressure fingers arranged to overhang the sheets as they progress to the registering fingers. 75 The fingers 19 are mounted on a transverse rock shaft 19' having its bearings in the brackets 14'. On one end of the shaft is a crank arm 20 which is jointed to a bar 21 having a roll 22 bearing on a cam 23 fast on the cylinder shaft. This cam is in such timed 80 relation to the adjacent cam 17 that the rock-shaft 19' and its fingers 19 are actuated to depress the sheets when the leading edges of the latter are in contact with the registering fingers.

As above indicated the sheets have heretofore been stacked on the bed 11 and then manually fed to the registering fingers preparatory to the engagement of the sheets 90 with the grippers of the cylinder.

In accordance with my invention I mount on the front of the bed 11 a platform 24 upon which the printed sheets are stacked, and I provide between the platform and the registering and pressure fingers novel mechanism whereby the sheets are removed from the pile or piles and delivered in an orderly manner to the said fingers. This mechanism, in its preferred form, is as follows:

25 designates a series of spaced-apart forwarding belts, the upper runs of which are inclined from the delivery end of the platform 24 to a plane in proximity to the pressure fingers. These belts are supported by 105 pulleys 26, 27 fast on cross-shafts 28, 29 having their bearings in suitably-disposed brackets 30, 31, respectively. Fast on one

end of the forward shaft 29 is a pulley 32 which is connected with a pulley 33 on a driven shaft 34 of the bronzing machine; the shaft 29 and its pulleys 27 thus being actuated to drive the belts with their upper runs travelling rearward, as indicated. In the present instance, two sets of forwarding belts 25 are arranged to receive the sheets respectively from two laterally adjacent piles on the platform 24.

35 designates a rock-shaft parallel with, and in a plane between and above the shafts 14, 19'. The shaft 35, which is journalled in brackets 36 on the sides of the main frame, is provided with a pair of upwardly and forwardly extending arm 37 to which are pivoted the rearward ends of a pair of parallel bars 38, the free ends of which overhang the delivery end of the platform 24 directly above the median lines of the respective piles of sheets. The bars 38 are provided with adjustable supporting brackets 39 for frictional feed rolls 40 that are adapted to bear, by gravity, upon the underlying sheets of the respective piles on the platform. Fast on one end of the rock-shaft 35 is a crank-arm 41 which is connected by means of a rod 42 with a wrist pin 43 on the cam 23 hereinbefore referred to. Hence during the rotation of the cylinder the shaft 35 is oscillated in a manner to effect the longitudinal reciprocation of the bars 38 and their feed rolls 40.

On each of the bars 38 in proximity to its forward end, is a laterally-disposed roll 44 which lies within a stationary casing 45 and travels longitudinally thereof during the reciprocation of the bar. This casing preferably comprises a channel member adjustably mounted, with its open side inward, on a bridge bar 46 having depending legs 47 that are rigidly bolted to the respective sides of the framework. In the present instance each channel member is provided with a pair of angle clips 48 which, when the casing is applied to the under side of the bridge bar, overhang the bar and are clamped thereto by bolts 49. By manipulating the bolts the clips can be released and the casing be adjusted along the bridge bar and clamped in any desired position. A strip 49' fixedly supported on the channel member, so as to depend adjacent the open side of the latter, serves to guide the bar and maintain it in operative relation to the said member.

To the inner vertical wall of each of the channel members is pivoted, as at 50, the forward end of a latch cam 51, the opposite end of which is downwardly inclined, as at 52, and rests by gravity on the bottom of the casing. The under side of the inclined portion of the cam lies in the path of the adjacent roll 44 when the bar 38 thereof is moved rearwardly. Fixed within the chan-

nel member is an inclined cam 53 which is spaced from the nose of the latch cam 51 and lies forwardly of and below the latter.

The co-operative relation of the parts above described is such that in the rearward stroke of the bars 38 the feed rolls 40 thereof bear upon the top sheets of the respective piles and by frictional contact pull such sheets rearwardly and deposit them upon the forwarding belts 25. In this stroke the lateral rolls 44 on the bars travel beneath and beyond the proximate latch cams, which cams are raised by the action of the rolls, but at once drop when the rolls clear them. Hence in the succeeding forward stroke of the arms such rolls ride upon and along the tops of the latch cams and temporarily maintain the bars in elevated position with their respective feed rolls 40 above the plane of the paper on the platform. As the bars 38 approach the limit of their forward stroke the rolls 44 escape the pivoted ends of the respective latch cams; the free ends of the bars perform drop, and the rolls 44 impinge against the opposing inclined cams 53 and travel down the latter until the feed rolls 40 come in contact with the proximate sheets on the platform. The cams 53 insure the accurate engagement of the descending feed rolls with the paper, since such cams by virtue of their angularity prevent the rolls from abruptly striking upon and rebounding from the sheets. The vertical range of travel of the roll bearing ends of the bars 38 between the bottoms of the respective casings and the pivoted ends of the adjacent latch cams, is, of course, sufficient to ensure the operation of the feed rolls upon the succeeding sheets from the top to the bottom of the respective piles.

The pivot studs 50 of the latch cams extend outwardly beyond the vertical walls of the respective casings and have affixed thereto the upper ends of downwardly and rearwardly extending rods 54 that overlie the paths of the respective sheets borne by the forwarding belts, and thus prevent upward displacement of the sheets.

Fastened to the underside of each of the casings is a forwardly and upwardly inclined strip 55 which serves as a guard to prevent the leading end of the sheet from catching on the casing as the sheet is being advanced from the pile by the feed roll; and rotatably mounted on the side wall of the casing is a small toothed or serrated wheel 56 which projects slightly into the path of the advancing sheet and thus obviates all liability of contact of the inked surface of the sheet with the strip.

While the sheets are progressing with the upper runs of the forwarding belts, the leading ends of the sheets encounter a row of upstanding pins 57 which act to straighten the sheets and "square" them on the belts,

which pins are thereupon depressed below the belts to permit the continued travel of the sheets. In the present instance the pins 57 project from a transverse rock-shaft 58 which is journaled in brackets 59 secured to the legs 47 of the bridge bar. Fast on one end of the shaft 58 is a crank arm 59' which is connected by means of a link 60 with a crank arm 61 on the shaft 14 which carries the registering fingers 12, and hence the pins 57 and the fingers 12 are actuated in harmony; that is, the pins are swung down to allow the sheets to continue their rearward travel, and at the same time the registering fingers are raised to permit the sheets which are in contact therewith to be engaged by the grippers of the cylinder 10; and conversely.

When the leading ends of the sheets escape the forwarding belts and progress to the registering fingers, such ends encounter the fingers 19 which are operable, as usual, to depress the sheets into position to be engaged by the grippers of the cylinder.

In order to insure the proper positioning of the edges of the sheets against the registering fingers 12, a series of vibratory depending fingers 62 are constructed and arranged to engage the trailing ends of the sheets as they approach the fingers 12. The fingers 62 are carried by a cross-shaft 63 which is located above the rearward ends of the forwarding belts, and has its bearings in brackets 64 mounted on angular supports 65 which are bolted to the respective brackets 30. The shaft 63 has at one end a depending pin 66 which is connected by means of a spring 67 to a pin on the adjacent support 65, which spring tends to maintain the shaft 63 in a position with the fingers 62 above the upper runs of the forwarding belts. A suitable pin 66' on the shaft contacts with a stud 68 on the adjacent bracket 64 and limits the upward movement of the fingers 62. In the present instance the brackets 64 are secured to the supports 65 by means of bolts 69 passing through longitudinal slots 70 in the supports so that such brackets can be readily adjusted horizontally in respect to the registering fingers so as to position the fingers 62 in accordance with the width of the sheets.

A flexible connection, as, for example, a chain 71, connects the pin 66 with the shaft 35 carrying the arms 37 for feeding bars, and hence in the impulse of such shaft to move the bars forward the chain effects a pull on the shaft 63 to swing the fingers 62 yieldingly downward and rearward against the opposing ends of the sheets on the forwarding belts, which sheets are thus pressed against and maintained in close contact with the down swung registering fingers. It is to be noted that the connection between the shafts 35 and 63 is made flexible because

the former has a greater movement than the latter shaft, which shaft 63 is provided with a limiting stop as above described.

It is to be understood that my invention is not limited to the specific construction 70 herein disclosed, as the mechanism may be modified within the principle of the invention and the scope of the appended claims.

I claim—

1. In a sheet feeding mechanism, the combination with a support for a stack of sheets, of forwarding belts adjacent said support, a bar having a sheet feeding member mounted to overhang the support, means for longitudinally reciprocating said bar to move said member toward and from the belts, means including a supporting element for imparting a rising and falling motion to said bar during its reciprocation, a forwardly and upwardly inclined guard strip extending from said element, and a serrated wheel adjacent to and projecting below the plane of said strip. 75

2. In sheet feeding mechanism, the combination with sheet registering fingers, and means for actuating the same, of forwarding belts leading toward said fingers, means for feeding sheets successively upon said belts, sheet positioning members movable above and below the path of the upper runs of the belts and operable to engage the trailing ends of the sheets as the sheets approach said fingers, and means for actuating said members in timed relation to the sheet feeding means and the registering fingers. 90

3. In sheet feeding mechanism, the combination with registering fingers operable to receive and position the leading edge of a sheet, and means for actuating the said fingers, of forwarding belts leading toward said fingers, means for feeding sheets successively upon said belts, oscillatory sheet positioning members spaced from the registering fingers and operable to engage and advance the trailing end of each sheet as the sheet approaches the fingers, and means for actuating said members in timed relation to the sheet feeding means and the registering fingers. 95

4. In sheet feeding mechanism, the combination with registering fingers operable to receive and position the leading edge of a sheet, and means for actuating the fingers, of forwarding belts leading toward said fingers, means, including a rock shaft, for feeding sheets successively upon said belts, means for actuating said rock shaft, oscillatory sheet positioning members spaced from the registering fingers and operable to engage and advance the trailing end of each sheet as the sheet approaches the said fingers and connections whereby the said members are oscillated during the operation of the said rock shaft. 110

5. In sheet feeding mechanism, the com- 130

bination with sheet registering fingers, and means for actuating the same, of forwarding belts leading toward said fingers, means, including a rock-shaft and a reciprocating bar, for feeding sheets successively upon said belts, sheet positioning means including members movable into and from the path of the upper runs of the belts and operable to engage the trailing ends of the sheets as they approach said fingers, a rock-shaft for said members, a resilient connection for said shaft operative to turn the latter to a posi-

tion with the said members in up condition when the reciprocating bar is moved rearward, and a flexible connection between the two shafts operative to turn the rock-shaft for the members in opposition to the action of the spring when the said bar is moved forward.

Signed at Barberton, in the county of Summit and State of Ohio this 14th day of January A. D. 1924.

EDWARD R. LINEBAUGH.
